Ernest Materna
ATTORNEY.

UNITED STATES PATENT OFFICE.

WALTER F. HEROLD, OF UPPER MONTCLAIR, NEW JERSEY, ASSIGNOR TO THE BASSICK COMPANY, OF BRIDGEPORT, CONNECTICUT, A CORPORATION OF CONNECTICUT.

CASTER-MOUNTING BRACKET.

Application filed January 5, 1926. Serial No. 79,328.

The present invention relates to an improved caster mounting bracket, particularly for use upon angle iron legs, cabinet constructions, open sided corner structures, and the like, such as are employed in washing machines, metal beds, and the like, an object of the invention being to provide a bracket of this character adapted to furnish a top center pintle bearing, and in which the load strain between such bearing and the supported structure may be transmitted in the most efficient manner, and side strain set up during movement of the furniture will not tend to twist or loosen the bracket.

To this end it is particularly proposed to provide a bracket in which the attaching rivets may be positioned below the top center bearing and in the direct vertical planes of the load strains, and further to provide a lateral area within the bracket constituting an unimpeded free space for the attaching of the rivets at the most desirable points for the efficient support of the load and side strains imposed on the bracket.

Heretofore such brackets have included pintle socket or securing means which extended vertically about the pintle in such manner as to necessitate attachment of the rivets in off-set relation to the vertical load strains, so that there was a decided tendency to distort and loosen the bracket and to impair the swivelling action of the caster.

A further object is to provide yieldable holding means at the bottom of the bracket for retaining the pintle, which will have no tendency to retard the swivelling of the caster, and further to provide such means which at no time is called upon to carry any stress due to side motion or side strains, so that such holding means is practically free of wear or deterioration.

A still further object is to provide a bracket in the form of a hanger having a top center bearing for the caster pintle, and having its ends extended directly beneath the end of the furniture leg, so that the load strain primarily taken up by the attaching rivets is secondarily transmitted directly to the bottom of the leg, so that there is practically no load strain on the bottom pintle retaining element, and it may therefore be made of relatively thin metal.

Other objects are to provide a bracket which may be economically formed from

sheet metal, and in which the metal may be so shaped as to effectually withstand the excessive loads and strains to which such devices are often subjected.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is an elevation of the inner side of a metal angle iron leg, having a bracket and caster, according to the present embodiment of the invention, attached thereto;

Fig. 2 is a rear elevation of the same with the caster removed;

Fig. 3 is a top plan view of the structure as shown in Fig. 2;

Fig. 4 is a bottom plan view thereof;

Fig. 5 is a vertical sectional view, taken along the line 5—5 of Fig. 3, and showing the caster pintle in place;

Fig. 6 is a perspective view showing the several parts of the bracket in separated relation;

Fig. 7 is a perspective view showing the parts of the bracket assembled; and

Fig. 8 is a plan view of a piece of sheet metal, and showing the manner in which a succession of pieces for forming the main part of the bracket may be cut therefrom in nested relation.

Similar reference characters indicate corresponding parts throughout the several figures of the drawings.

Referring to the drawings, the caster mounting bracket, according to the present embodiment of the invention, is adapted to be attached to the angle iron metal leg 10, and comprises a one-piece hanger including an upper horizontal portion 11 of substantially triangular shape, and side portions 12 and 13 bent downwardly at right angles thereto in right angular relation to each other, these portions 12 and 13 being spaced along their adjacent vertical edges in continuation of a diagonal edge 14 at the corner of the top portion which spans the rounded corner 15 of the leg, so that the bracket will fit snugly at the inner side of the leg, as clearly shown in Fig. 3.

The top portion 11 is projected outwardly

with respect to the outer vertical edges of the side portions, and is bent downwardly along a transverse line outwardly spaced from said vertical edges to form a reinforcing flange 16 adapted to render the top portion substantially rigid. A top center pintle bearing portion 17, of truncated cone shape, is pressed upwardly in the top portion 11, and is provided centrally with an inverted cone bearing center 18 pressed therein.

At their lower ends the side portions 12 and 13 are provided with downwardly extending tongues 19 adapted to be inserted through slots 20 in a base plate 21 and bent outwardly beneath the outer marginal edge portions of said plate. The base plate is of substantially segmental shape, its right angular edges being substantially flush with the outer edge of the leg, while its rounded edge 22 provides sufficient area within the bracket for carrying the pintle retaining means, presently to be described.

A pintle receiving opening 23 is provided in the base plate in axial alignment with the top center bearing. The pintle retaining means is carried upon the base plate, and in the present embodiment consists of a cup member 24 having a central pintle receiving opening 25 in line with the opening 23, and secured by projecting ears 26 inserted through slots 27 in the base plate and bent over upon the under surface thereof. Within the cup member there is loosely engaged and retained a split spring ring 28, its inner diameter being smaller than that of the openings 23 and 25, and its outer diameter smaller than the inner diameter of the cup member, this spring ring adapted, as will presently more fully appear, to retain the caster pintle frictionally.

The bracket is secured to the leg by means of rivets 29 engaged in holes 30 in the side portions 12 and 13 and holes 31 in the legs.

The detachable caster consists of the usual horn 32 having a caster wheel 33 rotatably carried therein upon an axle 34, and having a pintle 35 secured in its upper transverse portion, the lower end of the pintle being provided with a flange or shoulder 36 engaging the upper surface of the horn. The pintle is provided at its lower portion with an enlarged diameter cylindrical portion 37, tapering, as at 38, to the upper smaller diameter portion, and between said portion 37 and the shoulder 36 there is preferably formed a rounded fillet surface 39. At the upper end of the pintle there is provided a cone-shaped recess 40 adapted to rotatably engage the caster bearing 18 of the bracket.

The diameter of the pintle is such that the upper portion will pass freely through the spring ring 28, while the lower portion 37 will expand said ring and be thus held thereby against dropping out of the leg, the ring being snugly held about the pintle and freely

rotatable within the cup member 24. In the operative or engaged position of the caster, as shown in Figs. 1 and 5, the pintle has thrust bearing upon the center bearing 18 of the bracket, being held vertically by the base plate, the spring ring 28 firmly retaining it against dropping out, but permitting it to rotate freely within the socket without impedance. The ring may have any desired degree of frictional binding engagement upon the pintle, but in any case will have free rotary movement within the cup member 24.

It is obvious that with the present construction, having a top center bearing and a base retaining means spaced therefrom, that the inner surfaces of the side portions 12 and 13 are within an unobstructed lateral area, so that it is possible, with the pintle removed, to secure the rivets at any desired points therein, the free space within the bracket permitting the use of a riveting machine at the inner side of the leg. In particular, the construction permits the rivets to be so placed that their horizontal axes intersect the vertically disposed pintle, and the load strain transmitted from the upper bearing to the leg may be transmitted directly in the theoretically correct load strain lines. Thus any unbalanced strain is prevented and the chances of distortion and looseness eliminated. Obviously, where it has heretofore been necessary to apply the rivets in offset relation, the load strain was unbalanced, and side strain set up through movement of the furniture would tend to rock the bracket about its pivot points, impairing the swiveling action of the caster and causing looseness.

Inasmuch as the flange ends 19 extend directly beneath the leg end and take up secondary load strains, the base plate 21 is practically free of such strains, and may therefore be formed of relatively thin metal, or other suitable material.

In Fig. 8 I have illustrated the manner in which the right angular sheet metal blanks for forming the bracket frame may be cut in nested relation from a flat metal sheet, with no appreciable waste of material. The dotted lines in one of the blanks indicate the straight lines along which the side portions 12 and 13, and the flange 16, are adapted to be bent downwardly from the top portion at right angles, the edge portion 14 of one blank being coincident with the edge of the flange 16 of the next blank. Simultaneously with the bending operation the bearing portion 17 is preferably pressed into the top portion 11 by suitable dies.

I have illustrated and described a preferred and satisfactory embodiment of the invention, but it is obvious that changes may be made therein, within the spirit and scope thereof, as defined in the appended claims.

Having thus described my invention, what

I claim and desire to secure by Letters Patent is:—

1. In a furniture support mounting bracket for attachment to an angle iron support, a removable pintle element, a transverse sheet metal top portion including a pintle bearing portion, an attachment portion integral with and bent downwardly from said top portion, said top and attachment portions acting as a suspension support between the pintle and said angle iron support, a base plate having a pintle receiving opening and supported by said attachment portion in spaced relation to said top portion, the space between said top and base portions providing a laterally unobstructed pocket between said portions upon removal of the pintle whereby said attachment portion is laterally accessible at its inner side along lines intersecting the pintle when the latter is in place.
2. In a furniture support mounting bracket for attachment to an angle iron support, a removable pintle element, a transverse sheet metal top portion including a pintle bearing portion, attachment portions integral with and bent downwardly from said top portion at two adjacent sides in angular relation to said top portion and to each other, said top and attachment portions acting as a suspension between the pintle and said angle iron support a base plate having a pintle receiving opening and supported by said attachment portions in spaced relation to said top portion, the space between said top and base portions providing a laterally unobstructed pocket between said portions upon removal of the pintle whereby said attachment portions are laterally accessible at their inner sides along lines at right angles to said attachment portions and intersecting the pintle when the latter is in place.
3. In a furniture support mounting bracket for attachment to an angle iron support, a transverse sheet metal top portion including a pintle bearing portion, a pair of attaching portions bent downwardly from said top portion along two adjacent sides in angular relation to each other, a base plate having a pintle receiving opening and supported by said attaching portions in spaced relation to said top portion, said attaching portions being provided with end flange portions bent outwardly to an extent substantially corresponding to the metal thickness of said angle iron support to retain said base plate and
- adapted to engage directly beneath the lower end of said angle iron support, whereby thrust on said top portion is adapted to be transferred to said angle iron support, the space between said top and base portions providing a laterally unobstructed pocket between said portions whereby said attachment portions are laterally accessible at their inner sides.
4. In a furniture support mounting bracket for attachment to an angle iron support, a transverse sheet metal top portion having a pintle bearing pressed therein, vertical attachment portions integral with and bent downwardly therefrom along two adjacent sides in angular relation to each other, a base portion having a pintle receiving opening and supported by said attaching portions in spaced relation to said top portion, whereby said vertical attachment portions are laterally accessible at their inner sides.
5. In a furniture support mounting bracket a transverse sheet metal top portion having a pintle bearing portion, vertical attachment portions integral with and bent downwardly from said top portion at two adjacent sides at right angles to said top portion and at right angles to each other, a reinforcing flange bent from said top portion along a third side diagonally with respect to said attaching portions, a base portion having a pintle receiving opening and supported by said attaching portions in spaced relation to said top portion, whereby said vertical attaching portions are laterally accessible at their inner sides.
6. In a furniture support mounting bracket, a transverse sheet metal top portion having a pintle bearing portion, vertical attachment portions integral with and bent downwardly from said top portion in angular relation to each other, integral reinforcing means formed in said top portion in opposed relation to said attachment portions and transversely to a central vertical plane between said attachment portions, a base portion having a pintle receiving opening and supported by said attachment portions in spaced relation to said top portion, whereby said attachment portions are laterally accessible at their inner sides.

Signed at Bridgeport, in the county of Fairfield and State of Connecticut, this 22nd day of December, 1925.

WALTER F. HEROLD.
